ANTONIO DE ARMAS Y MANRIQUE AND FRANCISCO GONZALEZ DEL VALLE, OF HABANA,
CUBA

LOCK

Application filed July 5, 1928. Serial No. 290,419.

This invention is directed to an improvement in locks, particularly the cylinder type, in which provision is made for preventing cutting through the tumblers on the line of juncture between the casing and barrel for the unauthorized opening of the lock without the use of the usual key.

In cylinder locks of the conventional type, the tumblers are in sections which, in operative position, prevent the rotation of the barrel with respect to the casing, the use of the proper key so moving the tumbler sections that their junctures are in line with the juncture between the casing and barrel, thus permitting the latter to be rotated. It has been demonstrated that by drilling through the lock in the line of juncture between the barrel and casing and in line with the tumblers, the tumblers may be divided on this line and thereby permit the barrel to be freely turned for opening the lock without the necessity of using the proper key.

The primary object of the present invention is the provision of means tending to prevent the cutting or drilling of the tumblers of the lock along the particular line which will free the barrel.

The invention is illustrated in the accompanying drawings, in which:

Figure 1 is a view in elevation, partly broken out, showing a conventional form of cylinder lock provided with one form of means for preventing the drilling of the lock in line with the tumblers.

Figure 2 is a front elevation of the same.

Figure 3 is a section on line 3-3 of Figure 2.

Figure 4 is a perspective view of the barrel of the improved lock.

Figure 5 is a front elevation, partly broken out, of a cylinder form of lock provided with another form of means for preventing drilling of the lock in the line of the tumblers.

Figure 6 is a side elevation of the lock shown in Figure 5, partly in section.

Figure 7 is a side elevation of the barrel.

Figure 8 is an elevation of the key used with this type of lock.

Figure 9 is an enlarged front elevation of the protecting disk.

Figure 10 is a section of the line 10-10 of Figure 9.

Figure 11 is a side elevation of a conventional form of cylinder lock, partly broken out, and showing the lock provided with another type of means for preventing drilling of the lock in line with the tumblers.

Figure 12 is a vertical sectional view through the same on the line 12-12 of Figure 11.

Figure 13 is a side elevation of the barrel used with this type of lock.

Figure 14 is a perspective view of the protecting wedge.

Figure 15 is a longitudinal section through the lock, the protecting wedge being shown in place, the key being shown in place in initially applied position, the line of section being on line 15-15 of Figure 12.

Figure 16 is a broken view of the same, the barrel being turned to operate the lock.

Figure 17 is a broken elevation of the key used in this type of lock.

Figure 18 is a front elevation of a conventional cylinder lock showing a further modified form of protecting means.

Figure 19 is a longitudinal section on the line 19-19 of Figure 18.

Figure 20 is a vertical section of the upper section of one of the tumblers.

Figure 21 is a perspective view, partly broken out, of the same.

Figure 22 is a top plan of the same.

Figure 23 is a vertical section of one of the lower portions of the tumblers.

Figure 24 is a top plan of the same.

Figure 25 is a front elevation of a conventional form of cylinder lock, showing a further modified means of preventing drilling of the lock in the line of the tumblers.

Figure 26 is a side elevation, partly in vertical section, of the same.

The conventional cylinder lock embodies a casing 1 formed with an opening 2 for the reception of a barrel 3 having a keyway 4 for the introduction of a key of a particular type. The casing and barrel are formed with transversely ranging bores 5 which, when the barrel is in locked relation

to the casing, are adapted to be in alignment. In these bores are arranged tumblers including upper sections 6 and lower sections 7.

The respective sections of any one tumbler are designed to differ in length from the similar sections of other tumblers, so that with the lower ends of the sections 7 resting on the appropriate abutment in the keyway 4, the juncture between sections of any one tumbler is out of line with the juncture between the sections of other tumblers. Thus, the line of juncture between the barrel and casing is bridged at one or more points by a solid portion of either the upper or lower section of a particular tumbler and the barrel cannot be turned to open the lock.

The key, as illustrated for example at 8 in Figure 17, is formed in one edge with angular notches 9 of different depths and the lower ends of the lower tumbler sections 7 are of conical form to permit the key to be introduced so that each particular lower tumbler section will seat in the properly formed notch in the key. These notches are of such depth that when the key has been introduced, as illustrated for example in Figure 15, the respective tumbler sections are moved against the tension of springs 10 bearing upon the upper tumbler sections, so that the juncture between the upper and lower sections of all tumblers is directly aligned with the juncture between the casing and barrel. Therefore, the barrel is free to turn by a turning operation of the key and the lock may be opened.

With the line of juncture between the upper and lower sections of any tumbler out of line with the junction between the casing and barrel, the barrel cannot be turned, but it is evident that if the lock is drilled on the line of juncture between the barrel and casing, that is, on the line 11, with such line of cut in the plane of the tumblers, the tumblers will be divided and the barrel will be free to be turned to open the lock. The present invention is designed with a view to preventing a drill from dividing the tumblers and involves several different types of constructions tending to this important result.

In the form shown in Figures 1 to 4, the face of the lock, throughout an area preferably extending from the edge of the casing to the barrel, is formed with vertically ranging channels 12 which are V-shaped in cross section. These channels are parallel with their adjacent vertical walls meeting in the plane of the face of the lock in a ridge 13 defining a sharp edge extending throughout the full range of the channels.

The channels are so disposed that the maximum width of the channeled area is

greater than that of the tumblers of the lock and the ridge 13 is in line with the center line of the tumblers, the depressions of the respective channels being beyond the plane of the tumblers in each direction, as will be plain from Figure 3 of the drawings. 70

In this form of the lock, any attempt to drill through the tumblers will, in order to reach the tumblers, require that the drill be introduced exactly on the ridge 13, and as this ridge is in the form of a sharpened edge from which the walls of the depressions diverge, it is apparent that the drill will be directed to one side or the other of the line of tumblers and hence will not cut the tumblers to free the barrel. 75

In Figures 5 to 10 inclusive is shown another form of the invention, the conventional parts of the lock hereinbefore referred to being given the same reference characters in these figures as in the preceding figures. 80

In this form of the invention, the front walls 14 and 15 of the casing and barrel are together formed with a circular recess 16 in which is loosely placed a metallic disk 17. 90

The disk is of hardened metal and is of somewhat less diameter and thickness than the corresponding dimensions of the recess 16, so that the disk is substantially free in the recess. 95

The barrel is formed with an annular groove 18 forming a continuation of that portion of the recess 16 formed in the barrel, so that the barrel may be rotated without disturbing the disk. The disk 17, which may be of hardened metal, if desired, is formed in that face next the face of the lock with a depression 19 of conical formation and said disk is arranged in the longitudinal line of the tumblers of the lock. 100

In this form of the invention, it is apparent that any attempt to drill through the lock to cut the tumblers, as previously referred to, will be intercepted by the disk, and as the disk is free to rotate in its recess, it will simply move with the turning of the drill and the drill will not penetrate. The key 8 for this type of lock is provided with a cut-out portion 20 in the edge opposite the notches 9, which cut-out portion registers with the channel 18 in the barrel when the key is applied, thus providing a means in the key to receive the edge of the disk 17 when the barrel is turned after use of the proper key. 105

In Figures 11 to 16, we have shown another form of the invention, the conventional parts of the lock shown in these figures being identical with the given reference numerals similar to the same parts in the preferred form. 115

In this form, the casing and barrel are formed with a transverse wedge-shaped opening 21, that portion of the opening in the barrel being continued in the form of an 120

annular groove 22 in the barrel. A wedge key 23 is driven into the opening 21, the opening and key being of such relative form that the key is held securely in the opening in the casing, the lower edge of the key riding in the annular groove 22 in the barrel to avoid interference with the rotation of the barrel following the use of the proper key.

The wedge key 23 is of tempered steel and the opening to receive the wedge key is preferably arranged between the first and second tumblers of the lock, as more clearly shown in Figure 15. The wedge key thus bridges the line of juncture between the casing and barrel and any attempt to drill through the tumblers will be intercepted by the key, so that the tumblers in rear of the key with respect to the face of the lock cannot be reached by the drill. The operating key 8 is formed in the edge opposite the notches 9 with a cut-out portion 24 adapted to register with the annular groove 22 in the barrel when the key is in applied position, so that the barrel with the applied key may be turned without interference from the wedge key 23.

A further form of the invention is illustrated in Figures 18 to 24 inclusive, the parts in each of these figures which are similar to the conventional parts shown in the preferred form, bearing reference characters in agreement with such preferred form.

In this form, the respective tumbler sections 6 and 7 are constructed of tempered steel and provided with a metallic cover 25 to prevent their oxidation. The tumbler sections proper are formed with annular channels 26. Any attempt to drill through the tumblers will be prevented for the drill can not cut through the tumblers proper incident to their comparative freedom of rotation and, while the drill may penetrate the cover of the particular tumbler encountered, yet the freedom of the tumbler sections and their character will prevent cutting through such sections. In the event the rotation of the drill after perforating the cover tends to produce such movement of the tumbler section as might cause such section to move upwardly, it is apparent that when the drill encounters the channel 26, the rising tendency of the tumbler section will be thereafter prevented.

A further modification of the invention is illustrated in Figures 25 and 26, the conventional parts of the lock being indicated under the same reference numerals as in the preferred form.

In this form, the front wall of the casing 1 and barrel 3 are each formed with radial openings 27 and 28 respectively adapted to align when the barrel is in locked position in the casing. The tumblers 29 and 30 seat in these respective openings, these tumblers 65 being of hardened steel and while of such

length that they do not bridge the line of juncture between the casing and barrel, are nevertheless sufficiently close to such line as to intercept a drill operating on such line.

If desired, the openings or that portion of each between the proximate ends of the respective tumblers may contain a plastic filler 31, as wax, lacquer or the like, which will prevent the entrance of air or moisture tending to the oxidation of the tumblers 75 and 30.

In this form, the drill can not penetrate either tumbler 29 or 30 owing both to the character of such tumblers and their free rotative capacity in their openings, and hence the drill, if continued in operation, will be deflected beyond the line of the locking tumbler sections of the lock.

In each of the forms described, it is to be understood that the improvement is readily adapted and capable of application to a conventional cylinder lock. Each form of the invention serves to prevent the drilling of the lock in a way to cut the tumbler sections in order to free the barrel with respect to the casing; thus the lock is proof against such unauthorized opening and in some instances, particularly in the forms shown in Figures 5 to 10 and 11 to 16, the authorized key contains an additional construction over that necessary to operate the lock proper, thus further safeguarding the lock against unauthorized tampering.

What we claim to be new is:

1. A pin tumbler lock having the face thereof in line with the tumblers formed with spaced channels and an intermediate ridge having a sharp free edge.

2. A pin tumbler lock having the face thereof in line with the tumblers formed with spaced channels and an intermediate ridge having a sharp free edge, the base of the ridge being at least coextensive with and in alignment with the pin tumblers.

In testimony whereof we affix our signatures at Habana, Cuba, this fourth of May, 1928.

ANTONIO DE ARMAS Y MANRIQUE.
FRANCISCO GONZALEZ DEL VALLE.
